FOREIGN PATENT DOCUMENTS

EP 0595535 B1 3/1997

Primary Examiner — Rhea Shields(74) *Attorney, Agent, or Firm* — KDW Firm PLLC(57) **CLAIM**

The ornamental design for a low-profile cable armor, as shown and described.

DESCRIPTION

FIG. 1 is an isometric view of our new design;
FIG. 2 is a first side view of the design of FIG. 1;
FIG. 3 is a second side view and of the design of FIG. 1;
FIG. 4 is a first end view of the design of FIG. 1;
FIG. 5 is a second end view of the design of FIG. 1;
FIG. 6 is a top view of the design of FIG. 1; and,
FIG. 7 is a bottom view of the design of FIG. 1.
The broken lines in the drawings depict portions of the low-profile cable armor that form no part of the claimed design.
